UNITED STATES PATENT OFFICE.

WILLIAM L. R. EMMET, OF SCHENECTADY, NEW YORK, ASSIGNOR TO GENERAL ELECTRIC COMPANY, A CORPORATION OF NEW YORK.

SHIP PROPULSION.

1,095,461.

Specification of Letters Patent.

Patented May 5, 1914.

Application filed July 22, 1909. Serial No. 508,942.

To all whom it may concern:

Be it known that I, WILLIAM L. R. EMMET, a citizen of the United States, residing at Schenectady, county of Schenectady, State of New York, have invented certain new and useful Improvements in Ship Propulsion, of which the following is a specification.

My invention relates to the propulsion of ships and has for its object to provide such an arrangement of propelling or motive power apparatus that the ship can be operated economically with small power at cruising speed, and also operated economically with large power at maximum speed.

My invention is directed especially to the propulsion of war vessels, but it is also useful in connection with other classes of service.

In carrying out my invention in the present embodiment two propeller shafts are employed, but in certain cases one shaft may be employed and in other cases more than two. Mounted on each of these shafts is an electric motor and also a low-pressure, low-speed turbine, the latter being used as a general thing for high speed only of the ship. At cruising speeds the turbine will run idle in a vacuum or be disconnected. Between the rotor of the turbine and that of the motor a coupling is or may be interposed so that the turbine can be disconnected from the propeller shaft. The turbines are arranged to exhaust into a suitable condenser. I may condense all the steam in one condenser, or I may provide two or more condensers depending upon the distribution of the apparatus in the ship, and in using the term "condenser" I aim to include such arrangements.

At some suitable place in the ship one, two or more high-speed, high-pressure turbines are located, in the present embodiment two are shown, each of which drives an electric generator. These generators are connected to suitable conductors or bus-bars and the latter supply current to the electric motors on the propeller shafts. For one condition of operation, *i. e.*, cruising speed of the ship, the high-pressure turbines are arranged to exhaust into the same condenser that is used with the low-pressure turbines, and to exhaust into the low-pressure turbines and thence to the condenser for another condition of operation, *i. e.*, maximum

speed of the ship. For cruising conditions the high-pressure, high-speed turbines will alone extract the energy from the steam, but for high speed conditions they will extract only a portion, the remainder being extracted by the low-pressure, low-speed turbines. When the ship is driven at cruising speed, the propeller shafts are driven solely by electric power through the agency of the generators, motors and their connecting conductors, switches, etc. When the ship is driven at maximum or full speed condition, the driving is accomplished by means of the high and low pressure turbines, electric generators, electric motors and their connecting conductors, switches, etc.

Each of the high-pressure turbines is designed to operate at a high speed and one that is materially greater than is suitable for directly driving propeller shafts. This is attained by dividing the turbine into stages, properly proportioning the nozzles to convey the steam at the desired pressure and velocity and giving the buckets a shape and speed to extract said velocity as fully as practicable. By operating these turbines at high speed they can be made comparatively light and simple for their output, as can also the generators which are connected thereto. At full speed the high-pressure turbines may for example deliver a little over a fourth of the total power, the remainder being furnished by the low-pressure turbines.

I prefer to use multi-stage impulse turbines and particularly those of the Curtis type, since they possess many advantages in the way of high economy, simplicity of construction and reduced shaft speed. My invention, however, is not necessarily limited to impulse turbines, for I may employ reaction turbines, for example, of the Parsons type, or I may use machines that are a combination of the impulse and reaction types. The high-pressure turbines which I employ further possess the feature that they are designed to operate as condensing units for low powers and non-condensing units for high powers. To obtain this result each turbine is provided with two outlets or exhaust pipes, one leading directly to the condenser and the other leading to the admission end of a low pressure turbine. The conduit leading directly to the condenser is connected to the turbine casing at a point beyond the last row of wheel buckets. The conduit lead-

ing to the low pressure turbine is, on the other hand, connected to the high-pressure turbine casing at a point corresponding with one of the intermediate stages or a region 5 of intermediate pressure. The said pressure may be sixty or seventy pounds gage for example. In this conduit is an automatic valve that opens when the pressure in the particular stage or region of the turbine to 10 which it is connected exceeds a predetermined value and permits the steam to discharge into the low-pressure turbine instead of into the condenser. By providing this conduit and locating a pressure responsive 15 valve therein, the presence of an excessive or dangerous pressure in the high-pressure turbine is prevented and said turbine can pass automatically from condensing to non-condensing operation and vice versa. This valve 20 also permits of the low-pressure turbine running in a vacuum when power is delivered by the high-pressure turbine only.

When operating as a condensing unit, the 25 turbine should have a sufficient number of stages, each having the proper number of buckets operating at the necessary speed to extract the available energy from the steam. When operating as a non-condensing unit, the turbine should have the proper number 30 of stages and number of rows of buckets therein operating at the necessary speed to extract the available energy contained in the steam between its pressure of admission and that of the exhaust whatever the latter 35 may be. When the high-pressure turbine is of the impulse type, I prefer to provide it with a series of admission nozzles, some or all of which have suitable controlling valves operated by hand. At some point between 40 the high-pressure and the low-pressure portions of the turbine, means are provided for cutting stages into and out of service as by controlling the passage of steam through certain of the stage nozzles. This arrangement 45 also enables me to control the distribution of pressures in the various stages. When the turbine is operating as a condensing unit, some or all of these stage nozzles will be open and steam will pass 50 through all of the stages to the condenser, but when the machine is operating as a non-condensing unit, these stage nozzles will be closed and the steam will pass at a comparatively high pressure from an intermediate 55 stage to a low-pressure turbine. In other words, in the latter case, only a part of the stages of the high pressure machine are in operation, the remainder running idle in a 60 vacuum due to the connection to the condenser.

For the purpose of reversing the ship or driving it backward, the high-pressure, high-speed turbine may be provided with reversing buckets which are mounted on the 65 same shaft which carries the forward driv-

ing buckets. These buckets are arranged in stages of which one or more may be employed. The admission of steam to these buckets is controlled by a throttle valve, and, in addition, one or more nozzle valves 70 may be employed if desired. Since the high-pressure, high-speed turbines are connected only to the generators and not to the propeller shafts, it follows that the reversing and backing of the ship in this instance 75 are accomplished solely through the intermediary of the generator or generators and the electric motors. By reason of this arrangement the ship can be reversed by shutting off the main steam admission and admitting the steam to the reversing element. The electric generator and the motor are so organized and constructed that they will 80 operate in synchronism. This means that as the speed of the generator decreases to 85 zero as the steam supply is cut off, the speed of the motor will correspondingly decrease. The admission of steam to the reversing element then starts the generator into operation in the opposite direction, and with it 90 the rotor of the motor also in said direction. Since the rotor of the motor is direct-connected to the propeller shaft it follows that the direction of rotation of the shaft will 95 also be reversed.

I so design and construct the low-pressure turbine or turbines that it or they can operate at a shaft speed which is adapted for directly driving propellers, which speed is materially below that at which the high 100 pressure turbines can be effectively operated. I so arrange the rotor of the low pressure turbine or turbines that it will counter-balance the thrust of the propeller in large part. Such an arrangement will relieve the 105 thrust bearing, and hence a simpler design of thrust bearing may be utilized.

I prefer to employ alternating current, multi-phase generators of the synchronous type since these are well adapted for the 110 purpose intended and can be driven at high speed, which speed is best adapted with high-pressure turbines for effectively extracting energy from the steam. By using high speed generators, they can be made 115 relatively light and the size will be moderate for the output. I prefer to employ induction motors for the propeller shafts, each motor having a simple rotor of the squirrel-cage type. Such a motor will operate with 120 high efficiency. This motor will be wound with a greater number of poles than the generator, so that it will always rotate at a speed less than that of the generator. In addition to this, a pole changing means is 125 provided for changing the number of poles of the motor when it is desired to change the natural speed relation between it and the generator. For example, the generator may have two poles and the motor four 130

poles. This means that the motor will run at half the speed of the generator. If it be desired to further decrease the speed, the pole changing means may be shifted to so connect the windings that the motor will have eight poles, and the speed of its rotor will be correspondingly reduced with respect to the generator. By avoiding all circuit changing devices for the motor except the pole changers, the wiring of the system is a model of simplicity, and troubles incident to faulty operation of the electrical apparatus are reduced to a minimum.

Instead of reversing the ship by reversing the direction of rotation of the generator, and through it the motor, I may, under certain conditions, dispense with the reversing element on the high pressure turbine, and reverse the motors by means of suitable reversing switches placed in their circuits. In this event the generator turbine or turbines will always run in the same direction.

When a ship is operating at cruising speed, the power required is usually many times less than that required at the maximum speed and therefore, it will generally be desirable, when operating at cruising speed, to use only one turbo-generator unit to drive the motors, whereas it will be desirable to use two or more such units when the ship is operated at high speed. A high-pressure turbo-generator can readily be cut into and out of service by the throttle valve in the supply pipe and the switch connecting it to the bus-bars.

In order to control the speed of the ship whatever be the operating conditions, I vary the speed of the turbine driving the generator and thus maintain a state near synchronism of the electric generator and motor under all conditions of operation. This is one of the important features of my invention, since maintenance of such a condition affords maximum simplicity combined with highest efficiency.

The electric apparatus used can be of low voltage with the simplest and most direct connections. This affords a bond of ideal simplicity and effectiveness. Moreover the use of low voltages reduces the danger to life and property and also the necessary amount of insulation, the latter having a direct bearing on the initial cost and that of maintenance.

In case the ship is under way, and the low pressure turbine is disconnected from the propeller shaft, means may be provided by which a dangerous increased speed of the shaft of the low pressure turbine due to leakage from a source of supply will cause the main steam admission to be cut off. For this purpose I used an emergency stop valve in each main steam admission, and so arranged it that excessive speed of a low pres-

sure turbine or turbines will cause it to close. Since the low pressure turbine wheels can be operated in a vacuum by reason of the casing being connected to the condenser, the losses incident to leaving the rotors of the low pressure turbines connected to the propeller shaft will be very small, and the maximum adaptability can be obtained by running in this way.

If desired I can reverse the direction of the movement of the ship by installing a reversing element on the shaft of the low pressure turbine. If this is done, the low pressure turbine can be used alone as a means of propulsion whether in the forward or in the backward direction. Such a combination affords a means of propulsion in case of emergency, and is also very desirable for maneuvering.

Other features of my invention will be set forth hereinafter.

In the accompanying drawings which illustrate one of the embodiments of my invention, Figure 1 is a top view, partially diagrammatic, of my improved apparatus arranged to propel a ship; Fig. 2 is a partial axial section of the high-pressure, high-speed turbine; Fig. 3 is a partial axial section of the low-pressure, low-speed turbine; Fig. 4 is a detail view showing a reaction turbine adapted for use in my improved system; Fig. 5 is a detail view showing the apparatus as applied to one of the propellers with the low-pressure turbine equipped with means for reversing it and also with a connection for admitting live steam; Fig. 6 is a diagrammatic view of a separately excited turbine-driven generator; Fig. 7 is a detail view showing the means for cutting stage nozzles of a high pressure turbine into and out of service; and Fig. 8 is a diagrammatic detail view of an emergency stop valve controlled by speed governors driven by the shafts of the turbines.

Referring to Fig. 1, 10 and 11 indicate high-pressure, high-speed turbines. The former drives the three-phase alternating current generator 12, and the latter a similar generator 13. The rotors of each turbine and its generator are mounted on a shaft 14. The shafts 14 are entirely independent of the propeller shafts and rotate at a speed largely in excess thereof. Steam is admitted to the turbines by pipes 15, which are connected to the boilers. The exhaust of the turbines passes by the branched conduit 16 to the condenser 17, the auxiliaries being omitted to simplify the drawing. The conduit 16 is common to the forward driving and reversing elements of the high-pressure turbines. At some intermediate pressure point or stage the conduit 18 is connected to the casing of the high-pressure turbine 10 and extends to the low-pressure turbine 19. The high-pressure turbine 11 is

provided with a similar conduit 20, discharging into the low-pressure turbine 21. The conduits 18 and 20 are provided with automatic relief valves 22 and 23, each of which opens when the pressure in the predetermined stage or region in the high-pressure turbine exceeds a certain value, and discharges steam therefrom into its co-operating low-pressure turbine. When the valves 22 and 23 are shut no steam is admitted to the low-pressure turbines and the chambers therein are at the pressure due to the condenser.

The low-pressure turbines are permanently connected to the condenser by the conduits 24. The rotor of the low-pressure turbine 19 is mounted on a shaft 25 which forms a continuation of the propeller shaft 26. Between the propeller shaft and the turbine shaft is a coupling 27 of suitable construction. Mounted on the propeller shaft is the rotor 28 of an induction motor, the field or stationary part 29 being mounted on a suitable support. On the end of the shaft 26 is a propeller 30 of suitable shape, size and pitch. The low-pressure turbine 21 is connected to the propeller shaft 35 by the coupling 36. Upon the propeller shaft is mounted the rotor 37 of an induction motor, whose field, or stationary element 38, is mounted on a suitable support. On the end of the propeller shaft 35 is a propeller 39 of the same character as the one previously described. The generators 12 and 13 are connected in multiple by the bus-bars 40, and switches 41 and 42 are provided by means of which the circuits of either or both the generators may be controlled. To the bus bars are connected conductors 43 which supply current to the motors. The motors are connected in multiple with respect to the bus bars and conductors. Each motor is provided with a pole-changing device 44 by means of which the number of poles in its field winding can be changed and the fixed speed relation between it and the generator changed.

In order to reverse the direction of movement of the ship, each of the high-pressure turbines is provided with a reversing element to be described more fully hereinafter. I can reverse by using one or more of the turbo-generators. Steam is admitted to the reversing element of one of the turbines by a conduit 45 having a suitable throttle valve 46. Steam is admitted to the other turbine by a pipe 47 under the control of a throttle valve 48. As an additional means of governing the admission of steam to the reversing element, each turbine is provided with nozzle valves 49 that cut individual passages or nozzles into and out of service. Similar valves 50 are also provided for the high-pressure, forward driving portion of the turbines, whereby the speed of the tur-

bines can be varied by changing the number of nozzles in flow.

Under cruising speed conditions, the steam enters the high-pressure turbines and passes by the branched conduit 16 to the condenser. Under these conditions no steam will pass through the conduits 18 and 20. The current generated by the generators 12 and 13 is supplied to the induction motors which drive the propeller shafts. If the speed conditions are such that they do not require all of the power represented by the two turbines 10 and 11, I may cut one of these out of service and drive the ship solely by the other. The low-speed turbines may remain coupled to the propeller shafts, or they may be uncoupled at the couplings 27 and 36. Owing to the fact that the rotors of the low-pressure turbines revolve in an attenuated atmosphere, the rotation losses will be very small and in many cases for this reason it will be found undesirable to disconnect the low-pressure turbines. Assuming that it is desired to drive the vessel at maximum speed, steam is admitted to both of the high-pressure turbines and the ring or stage valves of both, to be hereinafter described, are moved in a direction to shut off their low-pressure portions. This results in building up the pressures in the stages to which the pipes 18 and 20 are connected to such a value as will cause the automatic relief valves 22 and 23 to open and discharge steam to the low-pressure turbines. Under these conditions all of the turbines and the generators and electric motors will participate in the propulsion of the vessel or ship. Since the lower pressure portion of each of the high-pressure turbines is shut off, and since said portions are exposed to condenser pressure, the rotation losses of the idle bucket wheels will be very small.

Referring to Fig. 2, I have shown one of the high-pressure, high-speed turbines provided with a suitable casing 31 that incloses the bucket wheels 51. The interior of the casing is divided into stages or wheel compartments by the diaphragms 52. In the present embodiment of my invention I have shown five stages, each stage having two rows of wheel buckets and a row of intermediates that is more or less annular, depending upon the volume of steam to be handled. The first two stages are designed and constructed to effectively extract energy from high-pressure steam. The last three stages are designed and constructed to effectively extract energy from steam of lower pressure. Steam is admitted to the first wheel by a nozzle 53 comprising a plurality of sections and these sections may each be controlled by a valve 50 as described in connection with Fig. 1. In the diaphragms are stage nozzles 55. 56 indicates the high pressure steam chest; 57 the

outlet to the pipe or conduit 18 or 20, as the case may be, leading to a low pressure turbine, and 58 the outlet connected to the branched pipe 16 and the condenser. 59 is the steam chest for the reversing element 60, which, in the present embodiment of my invention, comprises three rows of wheel buckets, and two rows of intermediate buckets. Steam is admitted to the buckets 10 by the sectional nozzle 61, each or all of the sections of which are under the control of the nozzle valves 49. Since this turbine is designed to operate a part of the time as a condensing unit, and a part of the time as a 15 non-condensing unit, a means must be provided for cutting out a certain number of stages. Such a means is found in the ring valve 62, to be more fully described in connection with Fig. 7. At present it is sufficient to say that by turning this ring valve in one direction or the other the number of stage nozzles in service can be varied from zero to a maximum.

When the high-pressure turbine is operating as a condensing unit, all five stages are in service, the steam passing from the steam chest 56 through all the nozzles and buckets and escaping by the outlet 58 to the condenser. When, however, large power is desired to propel the ship said turbine is operated non-condensing and the ring valve 62 is moved in a direction to close all the stage nozzles 63. Steam then enters by the steam chest 56, passes through the first two stages 30 of the machine, and passes by the outlet 57 and the pipe 18 or 20, as the case may be, to the low-pressure turbine where it acts on the buckets therein and the balance of the available energy is extracted after which it 40 exhausts into the condenser.

Referring to Fig. 3, I have shown a low-pressure, low-speed turbine. This turbine comprises a casing 65 that is divided into stages or wheel compartments by the diaphragms 66. Located within the stages are rotating elements 67, each of which carries rows of buckets with stationary intermediate buckets 68 between. In the first two stages there are three rows of buckets, each row being mounted on a disk, the disks being carried by a hub 69 that is mounted on the shaft 50. In the last three stages, the wheel construction differs in that two disks 71 are employed which support the ring 72. The 55 moving buckets are secured to the ring 72 by any suitable means. I have shown four rows of buckets mounted on the wheels of each of the last three stages, but I may employ a greater number in one or all of these 60 stages if desired. As a matter of fact, I prefer to employ more rows of wheel buckets, but owing to the small size of the drawing, I have not attempted to show as many rows of buckets as will generally be found 65 desirable in practice. The arrangement,

may, however, be taken as typical of any desired number of rows of buckets. Steam is admitted to the first stage by a sectionalized nozzle 73, and to the subsequent stages by sectionalized stage nozzles 74, the 70 cross-sectional area of the nozzles increasing from the inlet toward the exhaust to accommodate the increased volume of steam. All of the buckets in all of the stages of this machine may act on the impulse principle, or some of them may act by impulse and others by impulse and reaction. I find it preferable to so arrange the rotor that it counterbalances wholly or in large part the thrust on the propeller shaft due to the 75 action of the propeller. This result is obtained by having the pressure on one side of at least one of the low-pressure drums greater than that on the other, the side of the drum having the higher pressure being 80 away from the propeller, so that its unbalanced thrust due to steam pressure is against that of the propeller. In carrying out this feature of my invention, the nozzle end-pressure is made greater than that 85 at the point of discharge from the last row of buckets, and there is a corresponding drop in pressure in a step-by-step manner over the face of the wheel as the steam flows across it. I may incorporate this 90 idea in each of the stages of a low-pressure machine, or only in a portion of them. 75 indicates the admission orifice of the turbine that is connected to the pipe 18 or 20 as the case may be. 76 indicates an annular chamber which supplies steam to the admission nozzles 73. As a general proposition, the admission nozzles 73 will extend entirely or substantially around the turbine, 95 so that all of the wheel buckets will be 100 active. The necessary increase in cross sectional area of the working passage beyond the initial stage may be obtained by increasing the radial depth of the nozzles and buckets or by increasing the width of the 105 passages between the buckets measured in a circumferential plane by changing the entrance and exit angles of the buckets, or by both methods, whichever is preferable. The 110 particular manner in which the cross sectional area of the working passage is enlarged is immaterial so long as the passage does enlarge and does not unduly restrict or choke the free passage of the fluid. The steam from the last stage enters the discharge opening 77 from which it is conveyed to the condenser 17 by the conduit 115 24, Fig. 1.

Referring to Fig. 4, I have shown my invention in connection with a reaction type 125 of high-speed, high-pressure machine, that shown being of the well-known Parsons type modified in a manner to carry out my invention. For light load or cruising conditions, steam is admitted to the tur- 130

bine by the pipe 78 under the control of a throttle or other valve. The steam passes from the pipe 78 through the turbine acting on the successive rows of buckets until it is discharged by the conduit 79, which is connected to the pipe 16 leading to the condenser. For high or full-speed condition of operation, steam is admitted by the pipe 81 under the control of a throttle valve to the turbine at a point where the cross-sectional area of the working passage is greater than at the point of admission by the pipe 78 and escapes by the outlet 82 and pipe 18 to the low pressure turbine. This pipe is provided with an automatic relief valve such as described in connection with Fig. 1. When the turbine is operating under heavy load conditions, the buckets in the low-pressure end of the machine will be cut out of service by valves or other means acting to obstruct the passage of fluid therethrough and cause it to pass through the outlet conduit 82. A suitable arrangement for this will be described in connection with Fig. 7.

Referring to Fig. 5, I have shown a modification of my invention with respect to a low-pressure turbine. This figure shows the portion of the power plant on one side of the center line through the condenser. The portion of the plant on the opposite side of the center line is a duplicate of that shown and the two portions are connected in the manner indicated. It is arranged to be driven by steam exhausting from the high-pressure, high-speed turbine or by high-pressure steam directly from the boiler, or by a combination of high-pressure and low-pressure steam for forward driving of the ship. In other words, in this particular embodiment of my invention the low-pressure turbine is a mixed-flow or mixed-pressure turbine. Steam from the low-pressure source is admitted by the conduit 84 and from the high-pressure source by the conduit 85. This latter conduit supplies steam through the throttle valve 86 to the steam chest 87. The nozzles leading from the steam chest 87 have a greater expansion ratio than do the nozzles leading from the low pressure steam chest 88, the object of this being to reduce the pressure of the steam to that of the stage pressure into which it is discharged. The velocity of steam so discharged will be higher than that from the other nozzles but this will not interfere with the economy of operation, since whatever energy is not utilized in the first stage will be substantially utilized in the subsequent stages. In order to reverse the turbine and the ship, reversing buckets are mounted on one end of the turbine rotor, which buckets are reversely disposed with respect to those on the other end. The arrangement of the buckets of the reversing

element may be similar to that described in connection with Fig. 2. Steam is admitted to the buckets and their supply nozzles from the steam chest 89, under the control of hand valves 90. Steam from the high-pressure pipe 85 enters the steam chest by the conduit 91 under the control of a valve 92. When high-pressure steam is admitted to the turbine for the purpose of driving the ship forward, the valve 92 is closed and the valve 86 opened. When operated by low-pressure steam only, the valves 86 and 92 are closed. When it is desired to reverse the ship, the valve 86 is closed and the valve 92 opened, it being understood, of course, that the high-pressure turbine must be stopped. The arrangement of the motor on the propeller shaft, etc., is the same as that previously described, and the description need not be repeated.

In order to operate the electrical apparatus with high efficiency under light load conditions, *i. e.*, cruising speed, it is desirable to reduce the fixed losses to a minimum by changing the magnetic density of the iron in the generator. To this end I employ a separate exciter 93 for each of the generators, or one exciter may serve for all the generators. In circuit with the armature of the exciter is a resistance 94 which can be increased or decreased as it becomes necessary to vary the current flowing in the circuit to decrease or increase the magnetic density of the iron in the generator. The exciter is controlled by varying the resistance 95 in its field circuit. The exciter may be driven in any suitable manner, as, for example, by a small turbine or other engine.

Referring to Fig. 7, I have shown the ring valve 62 that has been previously referred to in connection with Figs. 2 and 4 for cutting sections of the stage nozzles 63 or the passages in a Parsons turbine into and out of service. This valve comprises a ring which has a central bore that engages a shoulder 96 on the diaphragm 97. A portion of the periphery of the ring is provided with teeth which mesh with a worm 98 by means of which the ring valve is moved angularly above its axis. The valve is provided with openings 99 and blank walls between said openings. When said openings are directly opposite the nozzles 63, shown in dotted lines, all the steam from the preceding stage or portion of the turbine will pass through said nozzles or passages, but as the nozzle openings or passages are cut off one by one by moving the ring valve angularly about its axis the effective opening is decreased. In the position shown, all of the nozzles or passages are out of service. This is the relation of parts when the high-pressure turbine is operating non-condensing.

Referring to Fig. 8, I have shown an au-

omatic stop valve which is located in the main steam pipe admitting steam to the turbines. When more than a single pipe is employed for admitting high-pressure steam to the turbines, one of these valves may be located in each of the pipes. The valve 100 is mounted on a stem 101, and the latter is screw-threaded into a sliding nut 102. The valve is unbalanced with a tendency to close due to the increased area of the lower part of the stem. The nut is normally held in position by the detent 103 so that by rotating the hand wheel in one direction or the other the valve can be opened and closed at will. In order to cause the valve to close suddenly in the event that the speed of one of the turbines becomes abnormal, a speed governor 104 is mounted on the turbine shaft 105. This governor comprises a ring that is so arranged that its periphery is normally concentric to the axis of the shaft, although its mass is not symmetrically arranged with respect to said axis, but as the speed increases abnormally, say 10 per cent., for example, the ring moves laterally with respect to the shaft axis against the action of a spring that tends to keep it concentric and engaging the lever 106 causes the member 107 to bridge the contacts adjacent thereto and to close the circuit of the solenoid magnet 108. The core of this magnet when energized pulls the detent 103 out of the notch in the nut thereby permitting the valve to close due to its unbalanced tendency, the nut 102 sliding down with it. To reset the valve, the hand wheel is first rotated in the valve-closing direction which raises the nut to normal position, after which the detent 103 is moved to the position shown, either automatically or by hand. After the nut is locked, the valve can be manipulated by the hand wheel the same as any other nut and screw valve. By using electric, mechanical or fluid-pressure means for transmitting the effects of the governor to the combined throttle and stop valve, the valve may be made responsive to the abnormal speed conditions of any one or all of the turbines, it being understood in the latter case that each turbine will have an emergency governor. The manner of arranging a second emergency governor 109 to energize the solenoid 108 is illustrated in Fig. 8. The valve will shut down the low-pressure turbine whether it is connected to the propeller shaft or not, provided its speed becomes excessive. Such a condition as this might exist if the low-pressure turbine was disconnected from the propeller shaft and steam were to leak through the conduit 18 or 20.

In addition to the advantages heretofore set forth my invention has the advantage of decreasing the initial cost and also the space occupied by the motive power apparatus. By improving the economy I reduce the nec-

essary number of boilers or the size of the boilers if the same number is retained, the space occupied thereby, and the coal consumption. The space thus saved can be used for coal bunkers thereby increasing the 70 cruising radius of the ship which is a factor of the greatest practical value. By careful calculation I find that I can about double the cruising radius of ships of certain designs. Owing to the character of the parts 75 of my improved system they can be arranged in the ship in a manner to obtain the best distribution of weight. I am also able to reduce the length of each of the propeller shafts, thereby reducing not only 80 the weight but the number of bearings employed.

I have employed the term "steam" to designate the motive fluid used to drive the turbines but it is to be understood that other 85 vapors having the same general characteristics as steam liberated by boiling water may be utilized.

I do not broadly claim the idea of reversing a propeller shaft which is driven 90 by an electric motor by reversing the direction of rotation of its generator and its prime mover since it is the invention of another, but limit myself to combinations in which this feature is an element. 95

The terms "high-pressure" and "low-pressure" as used in this case are relative. The former does not have reference to any particular pressure and neither does the latter. They simply mean that one is higher 100 than the other. The "region of intermediate pressure" referred to may have any desired value. It may be that of atmospheric pressure or it may be above or below that pressure. As a general thing it will be 105 found desirable to maintain this intermediate pressure at a value considerably above that of the atmosphere because with the arrangement described it results in a greater economy of operation for the different conditions of service than where a lower pressure is employed. 110

I have described certain arrangements of the turbines, generators and motors for obtaining certain speeds of the ship but it is 115 evident that other speeds can be obtained by proper modifications of the steam and electrical connections as will be understood from the foregoing description.

The feature of the emergency governing 120 mechanism herein described is not claimed because it forms the subject matter of my application Serial No. 802,145 filed November 18, 1913.

In accordance with the provisions of the 125 patent statutes, I have described the principle of operation of my invention, together with the apparatus which I now consider to represent the best embodiment thereof; but I desire to have it understood that the ap- 130

paratus shown is only illustrative, and that the invention can be carried out by other means.

What I claim as new and desire to secure by Letters Patent of the United States is,

1. In a system of ship propulsion, the combination of a high-pressure, high-speed turbine organized and constructed for condensing and non-condensing operation, an electric generator driven thereby, a low-speed, low-pressure turbine driven by steam from the first after it has passed through a portion only of said turbine, a propeller and its shaft direct-connected to the rotor of the low-pressure turbine, and a motor organized and constructed to rotate at a lower speed than the generator and receiving current therefrom, the rotor of the motor being mounted on the propeller shaft.

2. In a system of ship propulsion, the combination of a high-pressure, high-speed turbine, an electric generator driven thereby, a low-speed, low-pressure turbine driven by the exhaust from the first turbine, a propeller and its shaft direct-connected to the rotor of the low-pressure turbine, a motor organized and constructed to rotate at a lower speed than the generator and receiving current therefrom, the rotor of the motor being mounted on the propeller shaft, and a pole-changing means for changing the natural speed relation between the rotor of the motor and that of the generator.

3. In a system of ship propulsion, the combination of a high-speed, high-pressure turbine organized and constructed to operate as a condensing unit for low speeds of the ship and as a non-condensing unit for higher speeds of the ship, a low-pressure, low-speed turbine arranged to receive the exhaust from the high-pressure turbine when the latter is operating non-condensing, the rotor of the low-pressure turbine being adapted to be connected to the propeller shaft, a condensing means for the low-pressure turbine, a connection extending from the high-pressure turbine to the condensing means, a second connection extending from the high to the low-pressure turbine, a propeller shaft, a generator driven by the high-pressure turbine, and a motor on said shaft and driven by current from the generator.

4. In a system of ship propulsion, the combination of a main high-pressure turbine, a low-pressure turbine, the latter being driven by the exhaust from the former, an electric generator driven by the main turbine, a propeller and its shaft, an electric motor on said shaft which is driven by current from the generator, means for causing the main turbine, generator and motor to drive the propeller for one condition of service and both turbines, generator and motor to drive it for other conditions of service, and means for cutting a portion of the high-

pressure turbine out of service when the low-pressure turbine is receiving steam and is assisting in propelling the ship.

5. In a system of ship propulsion, the combination of high-pressure and low-pressure turbines, a conduit conveying the exhaust of the former to the latter, an automatic valve in the conduit responsive to pressure, an electric generator driven by the high-pressure turbine, a propeller and its shaft, an electric motor on said shaft which is driven by current from the generator, means for causing the high-pressure turbine, generator and motor to drive the propeller for one condition of service and both turbines, generator and motor to drive it for other conditions of service, and means for reversing the direction of rotation of the propeller and its shaft.

6. In a system of ship propulsion, the combination of a plurality of propellers and their shafts, high-pressure, high-speed turbines, electric generators driven thereby, low-speed, low-pressure turbines, one on each of said shafts which are adapted to receive the exhaust from the high-pressure turbines and be driven thereby, condensing means, electric motors mounted on the propeller shafts, conductors connecting the motors and generators, and switches arranged to connect the motors in circuit with one or more of the generators.

7. In a system of ship propulsion, the combination of a plurality of propellers and their shafts, high-pressure, high-speed turbines, electric generators driven thereby, low-speed, low-pressure turbines one on each of said shafts which are adapted to receive exhaust from the high-pressure turbines and be driven thereby, electric motors mounted on the propeller shafts, conductors connecting the motors and generators, switches arranged to connect the motors in circuit with one or more of the generators, and means for changing the natural speed relation between the rotors of the generators and motors.

8. In a system of ship propulsion, the combination of main turbines, each divided into high and low-pressure portions, low-pressure turbines, propellers and shafts therefor, electric generators driven by the main turbines, electric motors on said shafts, condensing means, means connecting the generators and motors to drive the shafts solely by electrical means at cruising speeds, means connecting the exhaust of the high-pressure portion of each main turbine with a low-pressure turbine, the two being arranged in series as to steam, means for causing the generators and motors to coöperate with the low-pressure turbines to drive the shafts at higher speeds of the ship, and means for reversing the direction of rotation of the propellers and their shafts.

9. In a system of ship propulsion, the combination of a high-pressure, high-speed turbine, a low-speed, low-pressure turbine, a condenser, a conduit leading from a region of intermediate pressure in the high-pressure turbine to the low-pressure turbine, valve means for controlling the flow of steam in the high-pressure turbine beyond said region, conduits connecting the exhaust openings of both turbines with the condenser, an electric generator driven by the high-pressure turbine, a propeller and its shaft, the latter being connected to the rotor of the low pressure turbine, an electric motor on the shaft which is connected electrically to the generator, and means controlling the admission of steam to the high-pressure turbine.

10. In a system of ship propulsion, the combination of a high-pressure turbine that is organized and constructed to operate as a condensing unit for lower speeds of the ship and as a non-condensing unit for higher speeds, a condenser connected to the outlet of the turbine, a low-pressure turbine that exhausts into the condenser, a conduit connected to a region of intermediate pressure in the high-pressure turbine and to the inlet of the low-pressure turbine, a valve in said conduit that is responsive to pressure changes, a propeller and its shaft, means for delivering the power developed by the turbines to the shaft, and a valve mechanism for controlling the admission of steam to the high-pressure turbine.

11. In a system of ship propulsion, the combination of a high-pressure turbine that is organized and constructed to operate as a condensing unit for lower speeds of the ship and as a non-condensing unit for higher speeds, a condenser connected to the outlet of the turbine, a low-pressure turbine that exhausts into the condenser, a conduit connected to a region of intermediate pressure in the high-pressure turbine and to the inlet of the low-pressure turbine, valve mechanism in the high-pressure turbine for shutting off its low-pressure portion when operating non-condensing, an automatic valve in said conduit which opens and discharges steam to the low-pressure turbine when the pressure in said region reaches a certain value, a propeller and its shaft, means for delivering the power developed by the turbines to the propeller, and a regulator for the high-pressure turbine.

12. In a system of ship propulsion, the combination of high and low-pressure turbines, the former operating at a higher speed than the latter, an electric generator driven by the high-pressure turbine, a propeller and its shaft driven by the low-pressure turbine, an electric motor which receives energy from the generator and whose rotor is

mounted on said shaft, condensing means, means for operating the high-pressure turbine as a condensing or as a non-condensing unit, means for controlling the admission of steam to the high-pressure turbine and therefore its speed, and means for varying the field excitation of the generator.

13. In a system of ship propulsion, the combination of a high-pressure, impulse, multi-stage turbine organized and constructed to operate as a condensing and as a non-condensing unit, means for cutting out certain of the stages when operating as a non-condensing unit, two exhaust conduits, one leading from an intermediate stage and the other from the last stage, a pressure responsive valve in the first conduit, the second being unrestricted, a low-pressure turbine receiving steam from the first named conduit, the high and low-pressure turbines operating with dissimilar speeds, condensing means receiving steam from the second named conduit and the low-pressure turbine, a regulator for the high-pressure turbine, a propeller and its shaft, said shaft being adapted to be direct-driven by the low-pressure turbine, and a speed reducing connection for transmitting the power developed by the high-pressure turbine to the propeller and its shaft.

14. In a system of ship propulsion, the combination of a high-speed, high-pressure engine, an electric generator driven thereby, a low-pressure, low-speed turbine, a propeller and its shaft direct-connected to the turbine, an electric motor mounted on the propeller shaft and constructed and organized to operate at a lower speed than the generator, conductors connecting the generator and motor, condensing means, conduit means discharging the exhaust steam from the engine direct to the condenser for conditions of low speeds of the ship, conduit means automatically discharging steam from the engine to the turbine for higher speeds after it has given up some of its energy in the engine and a regulator for controlling the speed of the ship both for low and high speeds which varies the admission of steam to the engine.

15. In a system of ship propulsion, the combination of a high-pressure, high-speed engine, a generator driven thereby, a low-pressure, low-speed turbine that is driven by the exhaust from the engine, a propeller and its shaft which are direct-connected to the turbine, a motor on the propeller shaft that receives current from the generator and is driven thereby, and a means for supplying live steam to the turbine to supplement its supply of exhaust steam, and to drive the turbine when the engine is idle.

16. In a system of ship propulsion, the combination of a turbine constructed and arranged to operate condensing and non-

- condensing, an electric generator driven thereby, a low-pressure, low-speed turbine that is normally driven by the exhaust from the first, condensing means for the turbines, 5 a propeller and its shaft connected to the rotor of the low-pressure turbine, an electric motor on the propeller shaft which receives current from the generator, reversing buckets mounted on the low-pressure turbine rotor, 10 means for admitting live steam to the reversing element when it is desired to reverse the ship, and means controlling the admission of steam to the turbine that drives the generator.
- 15 17. In a system of ship propulsion, the combination of a turbine constructed and arranged to operate condensing and non-condensing, an electric generator driven thereby, a low-pressure, low-speed turbine that is normally driven by the exhaust from the first, condensing means for the turbines, 20 a propeller and its shaft connected to the rotor of the low-pressure turbine, an electric motor on the propeller shaft which receives current from the generator, reversing buckets mounted on the low-pressure turbine rotor, 25 means for admitting live steam to the reversing element when it is desired to reverse the ship, means controlling the admission of steam to the turbine that drives the generator, and means for admitting live steam to low-pressure turbine.
18. In a system of ship propulsion, the combination of a turbine constructed and arranged to operate condensing and non-condensing, means for cutting a portion of the turbine buckets out of service for non-condensing operation, an electric generator driven by the turbine, a propeller and its 35 shaft, an electric motor mounted on the shaft which receives its current from the generator, the generator and motor driving the ship at certain speeds, a low-pressure turbine whose rotor is connected to the propeller 40 shaft, means for admitting steam from the generator-turbine to the low-pressure turbine 45
- when it is desired to propel the ship at higher speeds, condensing means for the turbines, and means for cutting the electrical apparatus out of service and admitting steam to the low-pressure turbine when it is desired to maneuver the ship.
19. In a system of ship propulsion, the combination of a high-pressure turbine, an alternating-current generator driven thereby, a low-pressure turbine, condensing means, conduit means for discharging steam from the high-pressure turbine to the condenser for operating it condensing and to the low-pressure turbine for operating it 50 non-condensing, a propeller and its shaft which are driven by the low-pressure turbine when it is receiving steam, an induction motor having its armature mounted on said shaft, the field winding of said motor receiving current from the generator, and means for changing the connections of the field winding of the motor to change the number of its poles.
20. In a system of ship propulsion, the combination of a high-pressure turbine having a bucket-carrying element, a generator driven thereby, a low-pressure multi-stage turbine receiving motive fluid from said high-pressure turbine and having a bucket-carrying element that exerts an axial thrust which opposes that of the propeller, a propeller and its shaft connected to said element, the bucket-carrying elements of the turbines rotating at different speeds, a motor on the propeller shaft receiving current from said generator, condenser means, means for operating the high-pressure turbine as a condensing or as a non-condensing unit, and means for controlling the admission of steam to the high-pressure turbine.
- In witness whereof, I have hereunto set my hand this 20th day of July 1909.
